TYPE-LOCK OF TYPE-WRITING MACHINES.

1,054,397.

Specification of Letters Patent. Patented Feb. 25, 1913.

Application filed December 29, 1911. Serial No. 668,434.

To all whom it may concern:

Be it known that we, GEORGE WILLIAM DAVIS and JOSEPH SOLOMON DUMAS, of the city of Westmount, Province of Quebec, in the Dominion of Canada, both subjects of the King of Great Britain, have invented certain new and useful Improvements in Type-Locks of Type-Writing Machines; and we do hereby declare that the following is a full, clear, and exact description thereof.

This invention relates particularly to that class of typewriting machines in which is employed a horizontally swinging type-lock having an arm adapted when the lock is operated to engage a part of the writing mechanism and prevent the operation of the latter, and a pair of arms engaged during the escapement-controlled feed, by a part upon the carriage for the purpose of successively arresting the carriage at two different distances from the end of the line. A key is arranged to act upon the lock to shift the same against the resistance of a spring and permit the operator to write a few more characters after having been stopped by the first arm of the pair, heretofore the second arm of the pair served as an abutment affording a final stop for the carriage. When the tabulator was carelessly used or the carriage otherwise, possibly by inadvertence, allowed to run freely without being arrested, by tabulator stops for instance, it would strike one or the other of this pair of arms and frequently damage the lock.

The object of the present invention is to relieve the lock of shocks of this nature and at the same time permit of its use under "escapement-feed" conditions to, as formerly, lock the machine successively at two different distances from the end of the line.

To this end the invention consists of means permitting the required movement of the lock to enable the latter to lock the machine when operated under "escapement-feed" conditions, and to come into action and displace the lock from the path of the member shifting it, when the carriage moves it more than the required amount.

For full comprehension, however, of our invention reference must be had to the accompanying drawings forming a part of this specification in which similar reference

characters indicate the same parts, and 55 wherein:

Figure 1 is a horizontal sectional view of the rear portion of a typewriting machine containing our invention, the section removing the writing mechanism, type-guide plate, and sufficient parts of the machine frame and carriage to clearly show the invention and its relation to the parts of the machine with which it co-acts; Fig. 2 is a transverse vertical sectional view taken 60 on line A A Fig. 1; Fig. 3 is a detail view illustrating in perspective the type-lock plate provided with our invention; Fig. 4 is a detail perspective view illustrating the supporting plate for the free end of the 65 locking plate.

The lock is in the main similar to the construction heretofore used, the present improvements being obtained by adding a structural feature thereto and placing a stop 75 on the carriage-supporting frame in position to most effectively transmit shocks exerted thereon to the machine frame. This lock consists of an oblong sheet-metal plate 2 slotted at one end as at 3 and having an 80 offset locking arm 4 extending downwardly from a lateral extension 5 at one side of the plate a short distance from the opposite end thereof, and a pair of angular arms 6, 7, extending downwardly from the opposite 85 side edge of the plate and having their ends turned beneath the latter. The end of the plate opposite the slot 3 is reduced in width to a narrow neck 8 formed with a diagonal finger 9. This device is slidably pivoted to 90 one side of the under-side of the upper portion 10 of the machine frame by a fulcrum-screw 12 through the slot 3, its opposite end with finger 9 thereon being supported in sliding contact with the opposite side of 95 the frame by an offset-plate 13 fastened in place by screw 14 and steadied in position by a lug 15 at one end engaging the face 16 of that portion of the frame. A pin 19 projects downwardly from the frame within 100 the space between the finger 9 and the body of the locking plate. The opposite end of this plate 13 terminates in a diagonal tail 17 perforated to afford a connection for one end of a retractile helical spring 18, the opposite end of which engages a perforation 20 in the locking-plate. The extension 5 rests in sliding contact with a boss 21 on

the frame and the arm 4, normally rests in close proximity to one side of the top of a boss 22 upon the feed-dog carrier 23. The function of the spring 18 is to yieldingly retain the locking plate in normal position with the end of its body portion abutting and the neck 8 bearing against the pin 19 and with the arm 4 in the normal position mentioned, viz., in close proximity to the top of boss 22. Under normal conditions the operator may, as heretofore, displace the locking-plate laterally, by a push-key 30.

The bell-trip, indicated at 40, is mounted 15 on the carriage, in position to trip on the turned-in ends of the arms 6 and 7 in succession. An angular stop 50 is rigidly fastened to the rear rail 51, of the carriage supporting frame in position to transmit 20 any shock exerted thereon to the end standard 52 of such frame and through it to the base of the main frame 53 of the machine.

During the operation of the machine, under straight writing conditions, during 25 which the carriage feed is controlled by the escapement, the bell-trip 40 engages the arm 6 when the carriage comes within a short distance of the end of the line, and the next action of the operator whether to print a 30 character or provide a space feeds the carriage one space with the effect that the locking arm 4 is moved just sufficiently to be placed over the boss 22 and as its elevation is practically equal to that of the top of 35 this boss, the latter, and the feed dog carrier, and consequently the writing mechanism, are locked against movement. The length of the neck 8 is slightly greater than one space and accommodates the movement 40 just mentioned. As the bell-trip engages the arms 6 and 7 under escapement feed conditions, it also strikes them when the carriage is released and allowed to travel under the full tension of the carriage-feeding spring 60, and in order to prevent damage 45 to these arms or the locking plate itself, the diagonal finger 9 is so arranged that the increased movement of the plate, due to the impact of the bell-trip on the first or 50 second arm (6 or 7), causes the cam face or the finger 9 to impinge upon the pin 19 and displace the plate laterally thereby releasing the bell-trip and allowing it and therefore the carriage to pass and be arrested 55 by the stop 50 which receives the entire shock due to the momentum of the carriage and transmits it to the rail 51, and through standard 52 to the base of the main frame of the machine. In this manner 60 the locking plate is relieved of all undue strain and in consequence is rendered more durable, and at the same time the loss of operator's time incidental to the repairing of the type-lock from damage due to being 65 struck by the carriage, is obviated.

What we claim is as follows:—

1. In a typewriting machine comprising a carriage with a trip device thereon and movable therewith, a device adapted to be engaged by the trip device upon the carriage when the latter nears the end of the line, and means automatically displacing the locking device from the path of the said trip device upon the carriage under different operating conditions. 75

2. A typewriting machine comprising a carriage having a trip-device thereon and movable therewith, a carriage supporting frame having a carriage-stop rigidly mounted thereon, a device for locking the machine and having an integral member in the path of the said trip-device, such locking-device being adapted to be moved by the trip device upon the carriage to locking position, and means formed integrally with 80 the locking device for automatically displacing the said locking device and moving the said member out of the path of the trip-device. 85

3. A typewriting machine comprising a 90 main frame, a carriage having a trip-device thereon, a carriage-supporting frame mounted upon the main frame and having a carriage-stop rigidly mounted thereon, a type-lock plate slotted at one end for sliding pivotal connection with the machine frame and having an arm intersecting the path of the trip-device, means slidably supporting the opposite end of the plate, means 95 yieldingly retaining the plate with its arm in intersecting position, and means whereby under certain conditions the said trip-device displaces the arm from intersecting position. 100

4. A typewriting machine comprising a 105 main frame, an operating part of the writing mechanism, a carriage having a trip-device thereon, a carriage-supporting frame mounted upon the main frame and having a carriage-stop rigidly mounted thereon, a 110 type-lock plate slotted at one end for sliding pivotal connection with the machine frame and having an arm intersecting the path of the trip-device and an arm for locking engagement with the operating part of the writing mechanism, means slidably supporting the opposite end of the plate, means 115 yieldingly retaining the plate with its first mentioned arm in intersecting position, and means whereby under certain conditions the 120 said trip-device displaces the arm from intersecting position. 125

5. A typewriting machine comprising a main frame, a carriage having a trip-device thereon, a carriage-supporting frame 125 mounted upon the main frame and having a carriage-stop rigidly mounted thereon, a type-lock plate slotted at one end for sliding pivotal connection with the machine frame and having an arm intersecting the 130

path of the trip-device, means slidably supporting the opposite end of the plate, means yieldingly retaining the plate with its arm in intersecting position, and means upon the 5 plate and engaging a part upon the frame whereby, under certain conditions, the said trip-device displaces the arm from intersecting position.

6. A typewriting machine comprising a 10 main frame having a pin projection, a carriage having a trip-device thereon, a carriage-supporting frame mounted upon the main frame and having a carriage-stop rigidly mounted thereon, a type-lock plate 15 slotted at one end for sliding pivotal connection with the machine frame and having an arm intersecting the path of the trip-device, means slidably supporting the opposite end of the plate, means yieldingly retaining the plate with its arm in intersecting 20 position, and the said plate having a cam face for engagement with the pin projection upon the frame whereby under certain conditions the said trip-device displaces the arm from intersecting position.

7. A typewriting machine comprising a main frame, having a pin projection, a carriage having a trip-device thereon, a carriage-supporting frame mounted upon the 30 main frame and having a carriage-stop rigidly mounted thereon, a type-lock plate slotted at one end for sliding pivotal connection with the machine frame and having an arm intersecting the path of the trip-device, means slidably supporting the opposite end of the plate, means yieldingly retaining the plate with its arm in intersecting 35 position, and the said opposite end of the plate having a neck and a diagonal finger for engagement with the pin projection upon the frame whereby, under certain conditions, the said trip-device displaces the arm from intersecting position.

8. A typewriting machine comprising a 40 main frame, an operating part of the writing mechanism, a carriage having a trip-

device thereon, a carriage-supporting frame mounted upon the main frame and having a carriage-stop rigidly mounted thereon, a type-lock plate slotted at one end for sliding pivotal connection with the machine frame and having an arm intersecting the path of the trip-device and an arm for locking engagement with the operating part of the writing mechanism, means slidably supporting the opposite end of the plate, means yieldingly retaining the plate with its first mentioned arm in intersecting position, and means upon the plate and engaging a part upon the frame whereby under certain conditions the said trip-device displaces the arm from intersecting position.

9. A typewriting machine comprising a main frame, having a pin projection, an operating part of the writing mechanism, a 55 carriage having a trip-device thereon, a carriage-supporting frame mounted upon the main frame and having a carriage-stop rigidly mounted thereon, a type-lock plate slotted at one end for sliding pivotal connection with the machine frame and having an arm intersecting the path of the trip-device and an arm for locking engagement with the operating part of the writing mechanism, means slidably supporting the 60 opposite end of the plate, means yieldingly retaining the plate with its first mentioned arm in intersecting position, and the said opposite end of the plate having a neck and a diagonal finger for engagement with the 65 pin projection upon the frame whereby under certain conditions the said trip-device displaces the arm from intersecting position.

Montreal Nov. 30th 1911.

In testimony whereof we have signed our 75 names to this specification in the presence of two witnesses.
